UNITED STATES PATENT OFFICE.

CHARLES GILBERT HAWLEY, OF CHICAGO, ILLINOIS, ASSIGNOR TO LOCOMOTIVE FIRE-
BOX COMPANY, OF CHICAGO, ILLINOIS, A CORPORATION OF DELAWARE.

LOCOMOTIVE BOILER.

Application filed October 3, 1924. Serial No. 741,311.

This invention relates to improvements in locomotive boilers and consists of the matters hereinafter described and more particularly pointed out in the appended claims.

5 The primary object of the invention is to provide a simple and efficient means in a locomotive boiler and preferably at or substantially in the transverse plane of the front throat or water leg thereof, to direct the cooler 10 boiler water at the bottom of the boiler into said front water leg and then into the side legs of the boiler where it is rapidly heated and caused to rise vertically in full contact with the side sheet and crown sheet of the 15 firebox and this without commingling with the cooler water circulating or moving aft toward the firebox.

A further object of the invention is to provide in the boiler a means which directs the 20 flow or movement of the cooler boiler water into predetermined courses which leads to the more efficient water heating surfaces of the boiler so that a definite path of circulation is established fore and aft of the boiler, 25 which the water must follow so that there will be no quiet or stagnant areas which will permit concentration of such agents in the boiler water that tend to pitting or corrosion of sheets and flues.

30 Another object of the invention is to provide in the boiler water space, a means which will insure equalization of boiler water temperature by causing active circulation thereof, so that stresses and strains on boiler structure which induces checks and cracks are 35 eliminated.

These objects of the invention, as well as others, together with the many advantages thereof, will more fully appear as I proceed 40 with my specification.

In the drawings:

Fig. 1 is a view in side elevation of the firebox end of a locomotive boiler, with part of the wrapper sheet shown as broken away to 45 more clearly illustrate the invention.

Fig. 2 is a transverse section through the firebox end of a locomotive boiler embodying my invention, as taken on the line 2—2 of Fig. 1.

50 Fig. 3 is a horizontal sectional view through the boiler, as taken on the line 3—3 of Fig. 1.

Referring now in detail to that embodiment of the invention illustrated in the accompanying drawings:—1 indicates as a whole the

shell or wrapper of the boiler and 2 indicates 55 the firebox thereof. The firebox includes the two side sheets 3—3 which merge into the transversely rounded crown sheet 4 and which extends from the rear sheet 5 to the flue sheet 6. To the flue sheet 6 are connected the usual 60 flues 7 and at the bottom of said flue sheet is an inside throat sheet 8.

The shell of the boiler comprises the outer 65 side sheets 9, a top sheet 10, a boiler wrapper 11 and front and rear outer throat sheets 12 and 13.

The various sheets of the boiler are suitably 70 stayed in any familiar manner and provide the usual front and rear water legs 14 and 15 and side water legs 16—16 which are closed 75 at their bottom ends by a mud ring 17. Of course, in the bottom of the firebox is the usual grate, not shown. The structure above described is typical of a locomotive boiler and is by way of illustration only.

In some locomotive boilers of the kind 80 above described, due not only to certain limitations and restrictions in design and arrangement of parts, as well as for other reasons, the circulation of water necessary to replace that evaporated by the firebox is not sufficient to prevent quiet or still areas so that certain elements or agents in the boiler water become deposited therein and induces corrosion of the 85 boiler parts at these areas.

Furthermore active circulation of the boiler 90 water in such boilers is not attained, with the result that temperature differences arise that set up unequal stresses resulting in increasing the cost of maintenance of the boiler.

To eliminate the objections to such boiler 95 conditions I provide in the boiler water space a simple and efficient means to direct the flow of the cooler boiler water into the front water leg and from there to the side water legs where 100 it is rapidly heated. Instead of permitting the water in the side legs, as it is heated, to intermingle with that part of the boiler water just above the throat, I confine the same so that it will travel directly upwardly in the side legs until it reaches the crown sheet, where it mixes with the hotter boiler water 105 at this point and moves forwardly. During this rapid heating, some of the water is evaporated into steam and in the forward movement of the water, it gives up its heat so that it descends toward the bottom of the boiler under the tubes.

In the embodiment of the invention, as herein illustrated I interpose in the boiler space and preferably at the junction of the side water legs and the boiler space above the front water leg, elongated right and left hand, vertically disposed plates 18-18, or what may be termed baffle plates. I find it most convenient to secure said plates to the boiler shell and for that reason each plate has a flange 19 which is secured to the shell by rivets or welding in a plane preferably in advance of the plane of the flue sheet. Said plates may be inclined inwardly and rearwardly toward the corner or junction of the flue sheet 6 and side sheets 3 of the firebox 2, and the free or unflanged edge of each plate is spaced a short distance from the firebox sheets. This spacing is not enough to permit a major circulation of boiler water between said corner parts of the firebox and said plates, but is just sufficient so that the edge thereof will not engage and abrade, or rub thereon in such relative movement as may occur between them and wide enough to keep clear of such scale. The top ends of said plates terminate in substantially the plane of the top of the firebox crown sheet, and the free margin of each plate 18 may be formed on an arc or curve corresponding to that of said crown sheet, while the bottom end of each plate extends substantially into the plane of the front water leg.

It is thus apparent that the structure herein described, causes the boiler water in the lower part of the boiler to enter the front water leg where it is directed into the lower parts of the side legs. The water is herein rapidly heated and a part thereof is evaporated into steam. Said water rises in the side and rear water legs to fill the same and as it cannot flow or move forward because of said baffle plates until it rises into a plane above the top of the same, it is maintained in contact with the efficient heating and evaporating surfaces of the firebox until it washes or floods over the crown sheet. This boiler water then flows forward, its temperature being reduced as the front ends of the tubes are reached when it settles toward the bottom of the boiler and flows rearwardly to replace the water directed inwardly into and heated and evaporated in the side water legs of the boiler. Thus a continuous and active circulation is imparted to the boiler water fore and after of the boiler and this continuous and active circulation not only equalizes the temperature of the entire body of water but insures against the forming of any quiet or still areas before mentioned.

It is believed that from the foregoing the many advantages thereof will be readily apparent to those familiar with the art and it is to be understood that the description of the formation, location and arrangement of the parts are given as illustrations, only, and is not intended for the purpose of limitation except as may be pointed out in the appended claims.

I claim:

1. In combination with a locomotive boiler shell and its self contained firebox separated by the usual water leg spaces, baffle plates carried by one of the first named elements and extending toward but being free from engagement with the other of the first mentioned elements for substantially closing off communication between the top portion of said side water legs and the forward boiler space. 70
2. In combination with a locomotive boiler shell and its self contained firebox separated by the usual water leg spaces, baffle plates carried by the boiler shell and extending toward but being free from engagement with the firebox and substantially closing off communication between the top portion of said side water legs and the forward boiler space. 75
3. In combination with a locomotive boiler shell and its self contained firebox separated by the usual water leg spaces, a vertical baffle positioned at the front end of each side water leg and terminating at its bottom at a point above the bottom of said leg and terminating at its top substantially in the plane of the top of the crown sheet said baffle being fixed along one margin to the boiler shell and being arranged with its other margin extending toward but spaced from the firebox. 80
4. In combination with a locomotive boiler shell and its self contained firebox separated by the usual water leg spaces, a vertical baffle positioned in each front water leg and extending diagonally thereof, said baffle terminating at its bottom at a point above the bottom of said leg and terminating at its top in substantially the plane of the crown sheet of the firebox said baffle being fixed along one margin to the boiler shell and being arranged with its other margin extending toward but spaced from the firebox. 100

In testimony whereof, I have hereunto set my hand, this 23 day of September, 1924.

CHARLES GILBERT HAWLEY.
